(57) **CLAIM**

The ornamental design for a baby bidet, as shown and described.

DESCRIPTION

FIG. 1 is a perspective view of the baby bidet showing my new design;

FIG. 2 is a front view thereof;

FIG. 3 is a left side view thereof;

FIG. 4 is a right side view thereof;

FIG. 5 is a top plan view thereof;

FIG. 6 is a bottom plan view thereof; and,

FIG. 7 is a rear view.

The broken lines in the drawings depict environmental subject matter of the baby bidet only and form no part of the claimed design.
